COMPRESSORS

The invention relates to a compressor with at least three stages, with a differential piston which is offset in cross section with an annular chamber communicating with a stepped cylinder, and with a high-pressure piston with a diameter of the order of preferably 5 to 25 mm.

The control of these high-pressure or needle pistons is very difficult. Known drives of such a high-pressure piston by means of a connecting rod results in transverse forces, causing bending and often also fractures. It is, therefore, known to mount these high-pressure pistons on special guide pistons with large cross section, actuated by a connecting rod, but this substantially increases the cost and the weight of the compressor. Moreover, transverse forces are still present so that fractures may still occur.

It is also known to eliminate these drawbacks by resting the high-pressure piston flush on a guide piston so that transverse forces are avoided. In this case the supply and removal of the pressure medium take place in the end face of the cylinder so as to retain the piston always on the guide piston. This results in great difficulties in the arrangement of the valves, particularly since this construction requires one valve in the inlet and another one in the outlet. In addition, the flow of the pressure medium, and particularly air, in the cylinder chamber is reversed.

In known compressors, all stages have their own pistons with their own piston rods, the dimensions of which are governed by those of the piston. Hence, the connecting rods for the high-pressure pistons must have very small dimensions. On the other hand, all connecting rods carry the same loads, and the weakest connecting rod of the high-pressure piston is therefore exposed to the risk of damage by overloads, and the bearings of this connecting rod suffer from accelerated wear.

The invention has the object of providing a compressor with at least three stages, with a high-pressure piston. Compared with hitherto known constructions, this compressor is characterized by its low weight, its better flow conditions, small air travel path and the elimination of transverse forces.

According to the invention this object is realized in that the differential piston acts as guide piston for the high-pressure piston. The invention is based on a construction, in which the suction chamber of the differential piston is on the side remote from the connecting rod, forming a large suction chamber, while the annular space is provided in a zone between the suction chamber and the connecting rod and the high-pressure piston passes through the suction chamber.

This differs from the known constructions with differential pistons, in which the piston section with the smaller diameter is arranged on the side remote from the connecting rod.

According to another feature of the invention, the high-pressure piston is mounted on the differential piston and is provided at its end with piston rings running along the cylinder, while its lower end runs in an annular seal provided on the cylinder. Thus, compared with known construction, in which the high-pressure piston must be lapped in, there is the possibility of a certain tolerance which prevents the occurrence of transverse forces even if the very accurate differential piston, guided in two places, should exhibit deviations. The use of a differential piston as guide piston represents, in view of the dual guide, an improvement compared with the known, otherwise functionless guide piston.

In view of these features, the high-pressure piston can be mounted rigidly on the differential piston. However, according to a preferred embodiment of the invention, the high-pressure piston is mounted resiliently on the differential piston. To this end, the differential piston has in its upper piston face a recess into which is fitted a flange of the high-pressure piston, means being provided to retain this flange resiliently, i.e., movable at least vertically, as well as reliably, in the said recess. This construction solves the guide problem of the high-pressure piston in a surprising manner.

Thus, the invention makes possible the manufacture of the high-pressure piston of light alloy, resulting in an excellent thermal flow to the differential piston which, owing to its mass, is particularly suitable for removing the heat. Hitherto, such high-pressure pistons had to be manufactured from steel with low thermal conductivity.

In another preferred embodiment of the invention, the root of the cylinder has a groove for the high-pressure piston, containing the annular seal along the smooth surface of which the high-pressure piston moves and which is resiliently backed by an O-ring mounted in the groove. The use of such a seal which is simultaneously suitable to act as a guide for the high-pressure piston, is an essential feature of the invention because it makes it possible to supply the cylinder chamber of the high-pressure piston through an inlet, located slightly above the point of reversal of the high-pressure piston. This eliminates not only the complex arrangement of an inlet valve on the high-pressure cylinder which has very small dimensions, but also prevents the reversal of the air flow in the high-pressure chamber of the compressor.

According to yet another preferred embodiment, the end face of the high-pressure cylinder is constructed as an outlet valve and a balanced flow is provided for the high-pressure chamber. This simplifies the construction and mounting of the outlet valve which may have a substantial cross section and does not, therefore, obstruct the operation by a rise in the temperature and the formation of eddies. The balanced flow has the same effect.

In yet another preferred embodiment of the invention, the cylinder head of the stepped cylinder forms the high-pressure piston and comprises also the inlet and outlet valves for the first stage and the supply for the high-pressure cylinder. In a preferred construction, the cylinder head is in two parts and has a closing plate for the stepped cylinder with the high-pressure cylinder and a cylinder head member with the inlet and outlet conduits into the stepped cylinder and with the supply conduit to the high-pressure cylinder, wherein this conduit has an annular groove surrounding the high-pressure cylinder equipped with radial orifices, adjacent to which groove are annular grooves provided with seals. This construction results in a particularly simple assembly. Conveniently, the cylinder head is also provided with oil vapor heating, connected to the crankcase, in the zone of the inlet orifice behind an air filter. This oil vapor supply ensures lubrication without any further equipment.

In a particularly preferred embodiment, the invention provides a three-stage compressor with a single-connecting rod, characterized by short air travels between the three stages and by the use of only a single cylinder.

This construction results in a much better performance than hitherto known constructions, while the weight is lower by about three-quarters.

The invention also comprises a further embodiment, in which one crankpin has mounted thereon two connecting rods for actuating a four-stage compressor with two differential pistons, of which at least one is a guide piston for a high-pressure piston, wherein the suction chambers of both differential pistons are connected with an annular chamber on one differential piston, and this annular chamber communicates with the other annular chamber of the other differential piston, and wherein this latter annular chamber is connected without intermediary of a valve with the inlet orifice of the high-pressure cylinder. Also here, there result the advantages of very short air travel paths, low weight and a reduction in valves. For example, if a three-stage compressor required hitherto six valves, of which two had to be fitted to the high-pressure piston, i.e., on its end face, the invention makes do with only five valves and saves further more also a connecting rod, compared with the known constructions.

According to another embodiment, at least two differential pistons with one high-pressure piston are mounted on a crankshaft and the suction chambers are each connected with an annular chamber, and at least two high-pressure cylinder

sections are connected in series. This leads to a substantial improvement, compared with known constructions, at lower loads with four stages; it should also be stressed that the individual high-pressure cylinder sections have the appropriate volumes.

In a preferred embodiment, there are provided two differential pistons with high-pressure pistons, each in a stepped cylinder, and both annular chambers are connected together to one high-pressure cylinder section which communicates in turn with the other high-pressure cylinder section. This achieves optimum utilization at substantially uniform load. In a further embodiment, there are provided three differential pistons; here, the annular chambers of all three cylinders are connected together by a manifold to two high-pressure cylinder sections, and these high-pressure cylinder sections communicate, in turn, with the third high-pressure cylinder section. This provides a substantial improvement of the volumetric output.

It should be pointed out that this is more particularly also the result of the fact that the flow through the high-pressure cylinder sections is unidirectional so that the compressors operate in this stage without the formation of eddies in one direction into a delivery device.

In the arrangement outlined above, the invention provides a four-stage compressor with three pistons in series arrangement. In the second embodiment mentioned, it provides a four-stage compressor with two pistons and two connecting rods, preferably in the arrangement of a V. The connecting rods are always hinged directly to the working piston and are of identical construction.

Conveniently, the volumes in the cylinder chambers change as a radical with always a higher index of the root. This results in favorable compression conditions.

According to an essential feature of the invention, the high-pressure piston is mounted on the differential piston and the high-pressure cylinder section has an inlet above the lower reversing point of the high-pressure piston and an outlet valve in the end face, and operates in unidirectional flow, wherein —and this should be particularly stressed—the outlet valve forms substantially the whole end face. In the preferred embodiment, the piston face of the high-pressure piston is guided in the immediate proximity of the valve seat of the outlet valve, and the valve body forms a sealing surface which is flush with the lower edge of the valve seat.

The term "immediate proximity" signifies an order of about one-tenth of a millimeter.

In principle, the invention includes a multicylinder construction, realized at choice either in V-shape or with opposed cylinders, wherein at least one differential piston carries a high-pressure piston.

Preferably, in a multicylinder construction, all cylinders have a differential piston and a high-pressure piston mounted thereon, operating in three stages, wherein the high-pressure stages of all cylinders, or the outlet conduits of all high-pressure stages are interconnected.

Further features and advantages of the invention will become apparent from the following description with reference to the accompanying drawings, in which:

FIG. 1 is a cross section of a three-stage compressor according to the invention;

FIG. 2 is a partial cross section of FIG. 1, drawn to an enlarged scale and showing a preferred guide of the high-pressure cylinder at its guided end;

FIG. 3 shows a special embodiment of the upper part of a stepped cylinder with differential piston and resiliently mounted high-pressure piston in cross section;

FIG. 4 is a cross section of the cylinder head in FIG. 3;

FIG. 5 shows the cylinder head part of FIG. 4, viewed from below;

FIG. 6 is a cross section of a multicylinder construction of a compressor;

FIG. 7 shows diagrammatically another arrangement of a multicylinder compressor;

FIG. 8 is a side elevation of a compressor with two piston-cylinder arrangements partly in cross section and partly in diagram;

FIG. 9 is a side elevation of a compressor with three piston-cylinder arrangements in series, partly in diagram and partly in cross section; and

FIG. 10 shows a detail of the cylinder head of the high-pressure piston.

In the drawings, the valves are merely indicated diagrammatically. Any valve used in this field of engineering can be used, such as, e.g., spring-loaded ball valves. The suction chamber, i.e., the low-pressure stage, is preferably controlled by leaf valves.

FIG. 1 shows a stepped cylinder 12, with a wider section 2 and a narrower section 3, and mounted on a crankcase 4, containing a driven crankshaft 5. The crankshaft 5 carries a connecting rod 6 for driving the differential piston 7; its narrower section is adjacent to the crankshaft 6, and is guided by means of piston rings 9, 10 in the part 3 of the cylinder 1. The piston section 11 with the larger cross section is guided by means of piston rings 12, 13 in the wider section 2 of the cylinder 1. The cylinder plate 14 is provided with a center bore 15, to which is connected flushly a cylinder 16 for the high-pressure piston 18, mounted on the end face of the section 11 of the differential piston 7 with larger cross section, e.g., by bolting.

The use of the differential piston 7 as guide piston for the high-pressure piston 18 with extremely small cross section, e.g., of 8 mm.; compared with a cross section of the piston 11 of 48 mm.; does not only result in only one connecting rod being required for all three stages, but also achieves that the positive guiding action of the high-pressure piston is effected by means of only one connecting rod, which can be strong and for which there is sufficient space for mounting the gudgeon pin in the differential piston 7.

In the cylinder plate are the inlet orifices 19 and the outlet orifices 20, controlled, for example, by leaf valves, as known in the art. The outlet is connected by a conduit 23 and a non-return valve 24 with the annular chamber 25 between the differential piston 7 and the cylinder 1. The inlet into this annular chamber is at 26 and the outlet 28 is controlled by a nonreturn valve 27. The outlet 28 communicates via the valve 27 and a schematically indicated conduit 29 with an inlet 30 into the cylinder 17, or the extension of this cylinder in the cylinder plate 14. This inlet is slightly above the lower reversing point of the high-pressure cylinder 18. Here, the supply takes place without the aid of a valve and is controlled by the high-pressure piston 18. This high-pressure piston 18 has only an outlet, controlled by a nonreturn valve 31, as shown by the arrow. Preferably, the outlet valve occupies practically the whole end face of the high-pressure cylinder 17.

This construction has the further advantage that the three valves 24, 27, 31 may have the same construction, which substantially improves the economy of manufacture. In addition, the short air travel paths may also be seen.

Surprisingly, it has been shown that, in conjunction with these short air paths, a vapor lubrication of the lowermost stage 4 is sufficient for lubricating the whole compressor.

Another advantage of this arrangement is that in the downstream oil-water separator a clear liquid is obtained so that a degree of purity is achieved which heretofore has been regarded as impossible. The oil-water separator is connected downstream of the whole compressor.

It may be seen from FIG. 1 that the high-pressure piston may carry on the top, for example, five piston rings 33. This piston is obviously mounted with clearance in the associated cylinder.

FIG. 2 shows that the cylinder plate 14 has, for example at the point indicated at 34 in FIG. 1, an annular groove 35 open towards the high-pressure cylinder. This annular groove has mounted therein, for sealing the high-pressure cylinder against the suction chamber and for guiding the high-pressure cylinder 18 m., a seal in the form of a closed ring 36. Preferably, this seal is made of a material based on

polytetrafluoroethylene, such as known under the Trade name "Teflon." This ring may have a rectangular cross section and a wall thickness of about 1 mm. It is backed by a conventional O-ring 37, mounted in the groove 36 and tightening the Teflon ring against the high-pressure piston 18. It has been shown that this provides a guiding action and a seal which meet the highest requirements.

FIG. 3 shows the upper end of a stepped cylinder. It is closed by a cylinder head, shown generally at 58. This cylinder head 58 is made in two parts and will be explained in details in FIGS. 4 and 5. It may also be seen that the high-pressure cylinder 60 is made integrally with at least one part, namely the closing plate 59, and is retained in its position by the fixing means 61, 62 of the cylinder head.

The differential piston 70 has in its upper piston face a cylindrical recess 63, with a bore 64 in the center thereof. The high-pressure piston 65 has at its lower end a flange 66 which engages with play into the recess 63. Below, the flange, the piston has a threaded pin, extending through the bore 64 and is mounted by means of this threaded pin 67 and a nut 68. Between the bottom of the recess 63 and the flange 66 there is a plastic plate 69, acting as seal. A spring washer 71 is arranged between the nut 68 and the differential piston 70, so that the high-pressure or needle piston is guided resiliently.

The cylinder head 58 (FIG. 4) consists of the closing plate 59 (FIGS. 4 and 5) and a fitted cylinder head member 72. Axial suction and inlet holes 73 with the leaf valve 74 arranged at the bottom of the latter and the outlet or delivery orifice 75 with a leaf valve 76 arranged on top pass through the closing plate. The plate also contains the fixing means for the spring leaves of valves 74, 76. In order to permit the movement of these valves, the space 77 above the outlet 75 is branched and terminates radially in a screw socket 78.

The space 79 above the inlet 73 terminates in a connecting socket 80 which may contain an air filter.

The high-pressure cylinder 81 is made integrally with the closing plate 59. It has radial bores 82 (corresponding to 30 in FIG. 1), at the level of which the cylinder head member 72 has an annular groove 83 into which leads a supply conduit 84, as shown in FIG. 5.

Above and below the annular groove 83, FIG. 4 are annular grooves 85, 86, provided with seals. A high-pressure cylinder head 87 (FIG. 3) is screwed to the upper end of the high-pressure cylinder 60 and carries an outlet valve 88.

An oil-vapor supply conduit 89, FIG. 5, leads into the chamber 79 and communicates, through means not shown, with the compressor crankcase.

The construction of FIG. 6 shows a twin-cylinder compressor. One cylinder corresponds to the three-stage compressor in FIG. 1, and is also marked with the reference numeral 1, identical parts having the same references. The other cylinder 38 is a differential cylinder containing a differential piston 39 and a connecting rod 40. Both cylinders 1 and 38 are arranged in V-shaped. The connecting rods are driven by a crankshaft 41, mounted in the crankcase 42.

In the cylinder plate 43 of the differential piston 38 there is a suction intake 45 controlled by a valve such as, e.g., a leaf valve 44, and an outlet 47 for the first or low-pressure stage 48, also controlled by a leaf valve 46. The outlet 47 communicates through a conduit 49, containing a valve 24, with the annular chamber 25 in the cylinder 1. This annular chamber forms the second stage. The outlet valve 27 of the annular chamber 25 communicates in the construction of FIG. 3, through the conduit 50 with the inlet 52 of the annular chamber 53 in the cylinder 38, controlled by a nonreturn valve 51. The annular chamber 53 forms therefore a third stage, the outlet of which communicates through a nonreturn valve 56 and a conduit 57 with the inlet 30 of the high-pressure cylinder 17 in which the high-pressure piston 18 is guided.

Obviously also the valves 51 and 56 may be constructed in the same way as the valves 24, 27, 31. Also this construction has short air paths and offers the advantages of the three-stage

compressor of FIG. 1. However, it provides a four-stage compressor with considerably raised output. It should also be pointed out that a four-stage compressor is here provided with only two connecting rods 6, 40, and one crankpin 41.

According to FIG. 7 two three-stage compressors according to FIG. 1 are mounted on one crankshaft. The stepped cylinders are shown at 1 and 91 and carry at their upper ends the high-pressure cylinders 17 and 92. This construction explains an arrangement with a conduit between the individual compressor chambers in FIG. 1, wherein however the outlet conduits from the high-pressure valves 31 and 93, shown at 94 and 95, are combined to form a common delivery conduit 96. This construction has the advantage of a rational assembly and of uniform loading of the driving parts. The arrangement of the valves corresponds to the other drawings.

In FIG. 8 two stepped cylinders 99, 100 are arranged in V-shape on a crankcase 97 with a crankshaft 98; each cylinder has a lower portion 101, 102, a part 103, 104 with larger diameter and a high-pressure cylinder section 105, 106 with a smaller diameter. The pistons are differential pistons with a shank 107, 108 and a wider section 109, 110, so that an annular channel 115, 116 is formed between the stage 111, 112 of the piston and 113, 114 of the cylinder. The suction chamber 117, 118 is arranged above the piston face. The high-pressure piston 119, 120 passes through the suction chambers 117, 118.

Piston rings are arranged at 121, 122; 123, 124; 125, 126. The pistons are connected by connecting rods 127, 128 with the crankshaft 98.

The inlets 129, 130 of the suction chambers are equipped with suction valves 131, 132, and communicate through delivery valves 133, 134 and conduits 135, 136 with the inlets 137, 138 of the annular chambers 115, 116. Nonreturn valves 139, 140 are arranged at these inlets. The outlets 141, 142 communicate through nonreturn valves 143, 144 with a conduit 145 which supplies a piston-controlled inlet 146, for example of the high-pressure cylinder section. The same communicates through an outlet valve 147 and a conduit 148 with the inlet 149 of the other high-pressure cylinder section 105, so that these two high-pressure cylinder sections 105, 106 are mounted one behind the other and the high-pressure pistons 119, 120 operate in series. The outlet valve 150 is mounted in an outlet conduit 151 and is mounted therein coaxially and over the entire cross section of the high-pressure cylinder section 105. The same also applies to the outlet valve 147.

FIG. 9 shows cylinder piston units in series arrangement so that only the connections between the different chambers need be described with reference to this figure. The suction chambers 152, 153, 154 have each an inlet 155, 156, 157. Their valve-controlled outlets 158, 159, 160 communicate through conduits 161, 162, 163 with the inlets 164, 165, 166 of the associated annular chambers 167, 168, 169. The valve-controlled outlets 170, 171, 173 of these annular chambers are connected to a common conduit 172 leading through a manifold 174, 175 to the inlet bores 176, 177 of two high-pressure chambers 178, 179. The valve-controlled outlets 180, 181 of these high-pressure chambers communicate through a manifold 182, 183 and a common conduit 184 with the inlet bore 185 of the third high-pressure chamber 186 of this compressor which operates through the valve 187 into the delivery conduit 188.

It may be seen that all cylinder piston arrangements are identical. They have each a differential piston 189, 204, 205 with a high-pressure piston 190, 206, 207, passing through the suction chamber 152 to 154. The identical connecting rods 191, 192, 193 are mounted on a crankshaft 194 in a crankcase 195. The crankshaft is driven by a motor 196.

FIG. 10 shows a high-pressure cylinder section 197 with a high-pressure piston 198. It may be seen that the valve seat 199 in the cylinder end face has substantially the same diameter as the cylinder chamber. The valve body 200 is so fitted that its end face 201, facing the cylinder chamber, is flush with the cylinder end face.

When the piston 198 reaches during its stroke the immediate proximity of the valve seat 199, any dead space is substantially excluded. This forms a substantial feature of the invention, in conjunction with the feature that the inlet is formed by radial inlets 202, 203.

I claim:

1. A multistage compressor comprising,
  - a. a low-pressure cylinder chamber having one end communicating with a high-pressure cylinder chamber,
  - b. a third chamber communicating with the other end of the low-pressure chamber, said third chamber having a diameter smaller than that of the low-pressure chamber,
  - c. a differential piston having portions of two different diameters, the larger diameter portion carrying piston rings and being slidable within the said low-pressure chamber and the smaller diameter portion carrying piston rings and being slidable within the said third chamber,
  - d. a high-pressure piston connected to the larger diameter portion of the differential piston, said high-pressure piston carrying piston rings at its free end and being slidable within the high-pressure chamber,
  - e. sealing means carried by the high-pressure chamber and cooperating with the high-pressure piston to seal the low-pressure chamber from the high-pressure chamber,
  - f. a first inlet valve and a first outlet valve at that end of the low-pressure chamber which is proximate to the high-pressure chamber,
  - g. a second inlet valve and a second outlet valve at the other end of the low-pressure chamber,
  - h. means forming a first air passageway between the said first outlet valve and the said second inlet valve,
  - i. means forming an inlet opening to the high-pressure chamber, which opening is positioned slightly above the lower dead center point of said high-pressure piston,
  - j. means forming a second air passageway between the said second outlet valve and the inlet opening to the high-pressure chamber,
  - k. a third outlet valve at the end of the high-pressure chamber, and
  - l. drive means for applying reciprocating movement to the differential piston.
2. The invention as recited in claim 1, including a crankcase communicating with the said third chamber and carrying a supply of oil; and wherein the said drive means comprises a connecting rod connected to the smaller diameter portion of the differential piston and to a crankshaft, said crankshaft dipping into the oil as it is revolved, and wherein said cylinder head is provided with an oil-mist supply passageway communicating at one end with the said first inlet valve and at the other end with the crankcase at a point above the level of the oil.
3. The invention as recited in claim 1, wherein the high-pressure piston is rigidly secured to the differential piston.
4. The invention as recited in claim 1, including means forming an axial hole in the larger diameter portion of the differential piston, which hole terminates in an enlarged diameter bore, an integral flange formed on the high-pressure piston and positioned in said bore, a resilient washer disposed between said flange and the base of the bore, and means retaining the said flange and the washer within the said bore.
5. The invention as recited in claim 1, wherein the said seal

ing means comprises an annular groove formed in inner wall of the high-pressure chamber, a resilient O-ring within said groove, and a polytetrafluoroethylene washer having a rectangular cross section and disposed between the O-ring and the high-pressure piston.

6. The invention as recited in claim 1, including a valve seat formed on the end of the high-pressure chamber; and wherein the said outlet valve at the end of the high-pressure chamber comprises a tapered valve body, the small diameter of said body being substantially the same as that of the high-pressure piston.

7. The invention as recited in claim 1, including a cylinder head comprising a first member constituting a closure plate for the low-pressure chamber and a second member secured to and concentric with the said first member; wherein the said first member carries the said inlet valve and said first outlet valve and includes a tubular portion which constitutes the high-pressure chamber, and wherein the said second member includes means forming a portion of the said first air passageway and means forming a portion of the said second air passageway.

8. The invention as recited in claim 7, wherein the said means forming an inlet opening to the high-pressure chamber comprises an annular groove formed in the said second member of the cylinder head, wherein the said groove communicates with radial holes passing through the said tubular member; and including a pair of annular seals positioned between the said first and second members and disposed to either side of the said annular groove.

9. The invention as recited in claim 8, including a crankcase communicating with the said third chamber and carrying a supply of oil; wherein the said drive means comprises a connecting rod connected to the smaller diameter portion of the differential piston and to a crankshaft, said crankshaft dipping into the oil as it is revolved, and wherein said cylinder head is provided with an oil-mist supply passageway communicating at one end with the said first inlet valve and at the other end with the crankcase at a point above the level of the oil.

10. The invention as recited in claim 1, in combination with a second, similar multistage compressor, a single crankcase communicating with each of the third chambers of the two compressors and carrying a supply of oil, a crankshaft dipping into the oil as it is revolved, and connecting rods connecting the differential pistons of the two compressors to the crankshaft.

11. The invention as recited in claim 10, wherein the outlet valves at the ends of the high-pressure chambers of the two compressors are connected by a conduit to form a common outlet for the two compressors.

12. The invention as recited in claim 10, wherein the said means forming the second air passageway also communicates with the corresponding outlet valve of the second compressor, and wherein the inlet opening to the high-pressure chamber of the second compressor is connected by a conduit to the outlet valve at the end of the high-pressure chamber of the other compressor.
